(74) Attorney, Agent, or Firm — Heslin Rothenberg Farley & Mesiti P.C.

(57) **CLAIM**

The ornamental design for a seat, as shown and described.

DESCRIPTION

FIG. 1 is a perspective view of a seat in accordance with the new design;

FIG. 2 is a front elevational view thereof;

FIG. 3 is a left side elevational view thereof;

FIG. 4 is a right side elevational view thereof;

FIG. 5 is a top view thereof; and,

FIG. 6 is a second embodiment of the seat comprising the new design, the sole difference between this embodiment and the first embodiment being merely a matter of length.

The broken lines in the figures are for illustration purposes only and form no part of the claimed invention.

1 Claim, 6 Drawing Sheets
